INVENTOR.

C. S. Rees

BY *Watson E. Coleman*
ATTORNEY.

UNITED STATES PATENT OFFICE.

CHARLES S. REES, OF FORT MYERS, FLORIDA.

PRIMING DEVICE.

Application filed December 17, 1923. Serial No. 681,192.

To all whom it may concern:

Be it known that I, CHARLES S. REES, a citizen of the United States, residing at Fort Myers, in the county of Lee and State of Florida, have invented certain new and useful Improvements in Priming Devices, of which the following is a specification, reference being had to the accompanying drawings.

10 This invention relates to priming devices and has for an important object thereof the provision of a simple, readily manipulated control device whereby an internal combustion engine may be primed in starting and supplied with auxiliary air during 15 operation.

A further object of the invention is to provide a device of this character having a single control element which by its operation controls the amount of air delivered to the engine either during the priming operation or during the supply of auxiliary air to the engine.

20 A still further object of the invention is to provide in a device of this character a casing adapted to contain fuel for supplying the engine during starting thereof, this casing being so constructed that a single control element associated therewith will 25 direct air admitted to the casing either into contact with this fuel for mixture with the fumes thereof or directly to the outlet of the casing so that it is unmixed with these fumes.

30 These and other objects I attain by the construction shown in the accompanying drawings, wherein for the purpose of illustration is shown a preferred embodiment of my invention and wherein:—

40 Figure 1 is a side elevation partially diagrammatic, showing a device constructed in accordance with my invention attached to the intake manifold of an engine:

Figure 2 is a vertical sectional view 45 through a preferred form of priming cup;

Figure 3 is a similar section taken at an angle to the first section, showing the device in the priming position;

Figure 4 is a plan view of the priming 50 cup, parts being broken away;

Figure 5 is a plan view of the cup with the valve disk removed;

Figure 6 is a vertical sectional view 55 through a slightly modified form of the invention;

Figure 7 is a similar view showing the

form disclosed in Figure 6 in the position in which air is admitted to the casing;

Figure 8 is a plan view of a further modified form;

Figure 9 is a plan view with the disk removed;

Figure 10 is a section on the line 10—10 of Figure 8; and

Figures 11 and 12 are sections on the line X—X of Figure 9, the disk being shown in closed and pure air feeding positions.

Referring now more particularly to the drawings, the numeral 10 indicates a control casing preferably provided with an attaching element 11 whereby it may be mounted at a point convenient to the operator of the engine as, for example, upon the steering post 12 of the vehicle and the casing maintained in a vertical position. This casing is provided in its lower end with an outlet 13 communicating through a conduit 14 with the intake manifold 15 of the engine at a point common to the cylinders 16 thereof.

The casing 10 consists essentially of a cup-shaped bottom portion or body 17 and a cap section 18. In Figure 2 the body portion is shown as having projecting upwardly from the bore 19 of the outlet 13 thereof a cylindrical baffle member 20, which baffle member 20 extends adjacent to but terminates short of the under surface of the cap member 18. The cap member 18 is shown as provided with a depending cylindrical baffle wall 21. While this wall is preferably carried by the cap it may be simply positioned thereby, as indicated in Figure 2, in which event it will extend entirely to the bottom of the casing and be provided adjacent its bottom with a plurality of openings 22 for the passage of air. Any desired means may be employed for positioning the baffle wall 21. In the present instance the under surface of the cap is shown as provided with a depending hub portion 23 accomplishing this result.

The upper surface of the cap has formed therein a pair of openings 24 and 25, the first communicating with the interior of the casing 10 interiorly of the baffle wall 21, while the second communicates with the interior of the casing exteriorly of the baffle wall 21. The upper surface 26 of the cap or closure 18 in this form of the device is preferably ground and provided centrally with an upstanding stud 27 forming a pivot upon which is mounted a rotatable valve disk 28 the under surface of which is ground

for coaction with the ground face 26. This valve disk has formed therein a series of openings 29 selectively alignable with the opening 24 of the cap 18 and with a single opening 30 alignable with the opening 25. This single opening is so arranged with respect to the series of openings 29 that when the openings 25 and 30 are aligned all of the series of openings 29 are out of alignment with the opening 24 and when any of this series is aligned with the opening 24 the opening 30 is out of alignment with the opening 25. The upper surface of the disk about the opening is preferably provided with a funnel 31, the purpose of which will presently appear.

The periphery of the disk is provided with a plurality of notches 32 selectively engageable with a spring latch 33, this latch yielding to permit rotation of the disk which rotation may be accomplished either by actually engaging the disk with the hand or by employing the funnel 31 as a handle. Each of the notches is provided with suitable indicia to indicate the results of positioning of the disk so that this notch is engaged by the spring latch 33. For example, one of the notches is indicated by O and indicates, when this notch is engaged by the latch 33, no air whatever is passing through the casing or through the conduit 14. Adjacent this notch are a pair of notches closely spaced and indicated as P¹ and P². When the latch is engaged with the first of these notches the priming opening 30 is aligned with the opening 25. When engaged with the second of these notches the opening 30 is out of alignment with the opening 25 and no air is passing through the conduit 14. The remaining notches correspond in number and arrangement to the series of openings 29 and are numbered accordingly so that each notch indicates the amount of air admitted to the opening 24.

In the operation of the device and in starting the engine, the disk is preferably arranged so that the notch P¹ is engaged by the latch 33 and a small quantity of priming fluid, such as gasoline, is pointed into the casing through the funnel 31. The engine is then operated to start the same with the result that air is drawn into the manifold through the opening 30 and must pass through the gasoline within the casing to reach the outlet 13 and conduit 14. During its passage it is mixed with the fuel so that a very rich mixture is admitted to the manifold, promoting starting of the engine. After the engine has started the disk is rotated to bring the notch P² into alignment with the latch in which position all openings are closed and in this position the engine is operated until it has heated and is running in a normal manner. After the engine has heated the disk is rotated in the

same direction to bring one or the other of the openings 29 into alignment with the opening 24 with the result that air is admitted to the casing without contact with the fuel contained within the casing, passing directly through the tubular baffle 20 to the outlet 13 and conduit 14. With this form of the invention it will be understood that the secondary air or auxiliary air, as it might be termed, has no mixture with the priming fluid after the engine has actually started. If desired the space between the inner tube or baffle 20 and the outer wall of the casing may be filled with fibrous material such as cotton, generally indicated at C in Figure 3. This fibrous material tends to retard the air and to cause the same to move in a tortuous path so that it is more thoroughly saturated with the priming fluid before leaving the casing.

In the form shown in Figures 6 and 7, the cap 18 has a threaded engagement through a flange 34 with the casing 17. The conduit 20 is of such length that when the cap is in its lowermost position it contacts against the upper end of the conduit 20 to close the same and prevent the passage of air therethrough. Through the cap 18 an opening 35 is formed exteriorly of the baffle wall 21, the upper surface of the cap being provided with the funnel 31.

With this form of device the fuel is admitted through the funnel and the cap rotated until the under surface of the cap is spaced from the upper end of the tube 20 a distance to permit the desired amount of air. The entering air passes through the priming fluid and out through the conduit 20 and conduit 14 to the manifold. After the engine has started the amount of air admitted may be reduced so that a small amount of highly charged air is admitted to the cylinders during that period in which the engine is warming up. After the engine has become warm the small amount of priming fluid admitted to the casing will become exhausted and at this time the admission of uncharged air can be advantageously resorted to with the result that air can be admitted through the opening 35 and pass through the conduit 20 to the conduit 14 to assist in the formation of the charge for the engine, this air being unaccompanied by any priming fluid. The amount of air so admitted may be so very closely regulated by means of the threaded engagement of the cap 18 and casing 17. In this form of the invention cotton or other fibrous material may be employed as shown in Figure 6.

In Figures 8 to 12 I have illustrated a further form of my invention. In this form the central baffle wall 20^a corresponding to the baffle wall 20 of the form previously described has formed in its lower end a circumferentially arranged group of small

openings 36. The baffle wall 21 is omitted forming a relatively large chamber 37 which is filled with cotton or similar fibrous material. The head of the cylinder is constructed after the manner of constructing the head in the form shown in Figures 2 to 5. The upper end of the baffle 20^a being enlarged, as at 38, so that the engaged portion of the head is of sufficient size to permit a ready formation of the opening 24 therein. The operation of this form of my device is exactly the same as that of the form originally described. The upper disk being rotated to successively bring the notches P¹ and P² into engagement with the latch to start and for a running position of the engine until the engine is heated, after which a selection of the openings 29 is effected.

It will be seen from the foregoing that a device constructed in accordance with my invention provides means for admitting a priming charge to the cylinders and for subsequently admitting a controllable amount of uncharged air to modify the charge received by the engine from the carburetor 40. It will furthermore be seen that structurally this device is capable of a considerable range of change and modification without in any manner departing from the spirit of my invention and I accordingly do not limit myself to such specific structure as hereinbefore set forth except as hereinafter claimed.

I claim:—

1. In a priming device, a casing provided in its bottom with an outlet, a cap for said casing, a cylindrical baffle extending upwardly from the outlet and in communication with the space between its outer wall and the wall of the casing, said cap being rotatably adjustable and by its adjustment selectively admitting air to the casing between the baffle and the wall of the casing or directly to the baffle, and means for admitting a priming fluid to the casing between the baffle and the wall of the casing.

2. In a priming device, a casing provided in its bottom with an outlet, a cap for said casing, a cylindrical baffle extending upwardly from the outlet and in communication with the space between its outer wall and the wall of the casing, said cap being rotatably adjustable and by its adjustment selectively admitting air to the casing between the baffle and the wall of the casing or directly to the baffle, and means for admitting a priming fluid to the casing between the baffle and the wall of the casing, said space having a filling of fibrous material.

3. In a priming device, a casing provided in its bottom with an outlet, a cap for said casing, a cylindrical baffle extending upwardly from the outlet and in communication with the space between its outer wall and the wall of the casing, said cap being rotatably adjustable and by its adjustment selectively admitting air to the casing between the baffle and the wall of the casing or directly to the baffle, and means for admitting a priming fluid to the casing between the baffle and the wall of the casing, said space having a filling of fibrous material, the baffle being provided in its lower end with a series of small openings.

4. In a priming device, a casing provided in its bottom with an outlet, a cap for said casing, a cylindrical baffle extending upwardly from the outlet to such cap, an opening in said cap between the baffle and the outer edge thereof, a second opening in said cap between the baffle and the center thereof, and means rotatable upon said cap for regulating the amount of air admitted to the casing through said openings.

5. In a priming device, a casing provided in its bottom with an outlet, a cap for said casing, a cylindrical baffle extending upwardly from the outlet to such cap, an opening in said cap between the baffle and the outer edge thereof, a second opening in said cap between the last named baffle and the center thereof, and means rotatable upon said cap for regulating the amount of air admitted to the casing through said openings, comprising a disk having an opening alignable with the first named opening and a series of opening selectively alignable with the second named opening, the series of openings being graduated as to size.

6. In a priming device, a casing provided in its bottom with an outlet, a cap for said casing, a cylindrical baffle extending upwardly from the outlet to such cap, an opening in said cap between the baffle and the outer edge thereof, a second opening in said cap between the baffle and the center thereof, and means rotatable upon said cap for regulating the amount of air admitted to the casing through said openings, comprising a disk having an opening alignable with the first named opening and a series of openings selectively alignable with the second named opening, the series of openings being graduated as to size, and means for maintaining the first named opening of the disk partially or fully aligned with its co-acting opening of the cap.

In testimony whereof I hereunto affix my signature.

CHARLES S. REES.
